UNITED STATES PATENT OFFICE.

RICHARD LORD, OF CEDAR RAPIDS, IOWA.

TANK-HEATER.

1,239,925.

Specification of Letters Patent. Patented Sept. 11, 1917.

Application filed February 12, 1916. Serial No. 77,875.

To all whom it may concern:

Be it known that I, RICHARD LORD, a citizen of the United States, residing at Cedar Rapids, in the county of Linn and State of Iowa, have invented new and useful Improvements in Tank-Heaters, of which the following is a specification.

This invention relates to tank heaters and consists in certain improvements in the construction thereof as will be hereinafter fully described and pointed out in the claims.

More particularly the invention relates to that type of tank heaters which comprise a stove capable of being submerged in the tank for burning such fuels as wood and coal.

The invention is illustrated in the accompanying drawings as follows:—

Figure 1 shows a vertical section just inside of one of the side walls with the heater arranged for coal.

Fig. 2 a similar view with the heater arranged for wood.

The heater body is formed in one piece having the bottom 1, ends 2 and 3 and sides 4. Extending upwardly from the fire chamber which is ordinarily entirely submerged is an entrance projection 5 on which is arranged a cover 6.

The fire box 7 is preferably removable and has the rear perforated wall 8 forming a combustion chamber 9 to the rear of the fire box. A chimney 10 extends along the top of the fire box, the lower wall of the chimney forming the upper wall of the fire box. It has the upwardly formed extension 11, one wall of which is formed by the wall of the upper projection 5. A pipe 12 is arranged in the upward extension 11.

The formation of a combustion chamber to the rear of the fire chamber is desirable in that the gases liberated from the coal are here consumed. By making one wall of the chimney the upper wall of the fire chamber a constant draft is assured and at the same time in a one piece body such construction may be more readily formed. To this end also it is desirable to have the upright portion 11 have one wall of the chimney integral with the upright or projection 5. By putting the chimney 12 inside of the upright 11 any condensation from the chimney is carried into the upright 11 and this prevents its dripping into the tank and thus tainting the material being heated. The draft flue 18 is formed along the wall of

the fire chamber and projection, one wall of this draft flue being the wall 2 of the fire chamber. It has an opening 19 into the fire chamber near the bottom.

A draft plate 14 is provided and is of such size that in burning coal it will rest on a ledge 7^a on the front of the fire box. It may be swung to the position shown in dotted lines in Fig. 1 for filling the fire box or to the position shown in solid lines in Fig. 1 for removing the ash pan 13 which occupies a position under the fire box.

I prefer to provide the projections 15 on the wall 2 and the projection 16 along the bottom of the upwardly extending projection 5 and to have the plate 14 of such size that it will rest on the projections as shown in Fig. 2. If desired, the cover 6 and the plate 14 may be connected with a chain 17 so that the opening of the cover will also open the plate 14. This forms an insulating chamber when wood is being burned, thus confining the heat to that portion of the fire box with which the liquid comes in contact and also making a tighter closure so as to control the fire. It also keeps the cover cool enough so that it may be readily handled in introducing wood.

The plate 14 when used as shown in Fig. 1 insulates the fire and makes an air space insulating the major portion of the projection 5 thus conserving the heat. Inasmuch as all of the heater is submerged all the heat that may be given off is given off to the liquid.

I have shown in the figures the heater as arranged in a tank A. The heater preferably has the legs 20 which lift the bottom slightly off the tank floor. Space, therefore, is afforded for liquid and to the extent that the base of the heater gives off heat this adds to the efficiency of the heater and at the same time raising the heater from the floor of the tank adds to the safety in the use of the heater. This is particularly effective where wood is used directly on the floor of the heater.

What I claim as new is:—

1. In a tank heater, the combination of a one-piece body having a fire chamber; an upwardly extending entrance projection; and a chimney extending along the top of the fire chamber and having its lower wall formed with the upper wall of the fire chamber.

2. In a tank heater, the combination of a

body having a fire chamber; an upwardly extending entrance projection; ribs arranged in the projection; a fire box; and a plate adapted to rest on the fire box and of a size to fill the opening above the ribs.

3. In a tank heater, the combination of a body having a fire chamber; an upwardly extending entrance projection; supporting ribs arranged in the projection; a removable fire box; a plate adapted to rest on the

fire box and extend into the projection, said plate being of a size to fill the opening above the ribs when placed upon said ribs; and a chimney extending along the top of the fire box and having its lower wall 15 formed with the upper wall of the fire box.

In testimony whereof I have hereunto set my hand.

RICHARD LORD.
